UNITED STATES PATENT OFFICE.

ARTHUR L. TRUITT, OF LEWES, DELAWARE.

UMBRELLA.

1,177,739.

Specification of Letters Patent.

Patented Apr. 4, 1916.

Application filed June 24, 1914. Serial No. 847,116.

To all whom it may concern:

Be it known that I, ARTHUR L. TRUITT, a citizen of the United States, residing at Lewes, in the county of Sussex and State of Delaware, have invented certain new and useful Improvements in Umbrellas, of which the following is a specification.

This invention relates to an umbrella and the principal object of the invention is to provide improved means for bracing the ribs of an umbrella so that the umbrella cannot be turned inside-out by strong wind.

Another object of the invention is to so construct the braces of the ribs that the stretchers may pass through the braces, thus preventing the ribs and stretchers from moving out of the desired position.

Another object of the invention is to so construct the umbrella that the ribs and stretchers will be independently braced and thus a very strong umbrella frame provided.

This invention is illustrated in the accompanying drawings, wherein—

Figure 1 is a view showing the frame partially closed and shown in elevation; Fig. 2 is a view similar to Fig. 1 but showing the frame in the open position; Fig. 3 is a top plan view showing the frame in the open position.

The staff 10 is provided with the usual notch 11 and slide 12 with which the ribs 13 and stretchers are connected. A sleeve 15 is slidably mounted upon the staff beneath the slide 12 and is provided with collars 16 and 17 which are similar to those carried by the sleeve and notch.

In order to brace the ribs and stretchers there is provided braces 18 and 19 which are pivotally connected with the collars 16 and 17 and have their outer ends pivotally con-

nected with the ears 20 and 21 of the stretchers and ribs. The braces 19 are tubular in shape and are provided with longitudinally extending slots through which the stretchers 14 pass so that the stretchers and braces 45 will be prevented from having independent transverse movement, thus preventing the ribs and stretchers from moving out of the desired position. It will thus be seen that the ribs and stretchers will be very securely 50 braced, the ribs being braced by the stretchers and braces 19 and the stretchers being braced by the braces 18. Therefore the frame of the umbrella will be very securely 55 braced and prevented from being turned in- side-out by a strong wind.

What is claimed is:—

An umbrella frame comprising a staff, a notch rigidly mounted upon said staff, a sleeve slidably mounted upon said staff and 60 provided with upper and lower collars, a slide slidably mounted upon said staff between said sleeve and notch and provided with a collar, ribs pivotally connected with said notch, tubular braces pivotally connected with said ribs and with the upper collar of said sleeve, said tubular braces being provided with longitudinally extending slots, stretchers pivotally connected with the collar of said slide and passing through 70 the slots of said braces and pivotally connected with said ribs, and braces pivotally connected with said stretchers and the lower collar of said sleeve.

In testimony whereof I affix my signature 75 in presence of two witnesses.

ARTHUR L. TRUITT.
